UNITED STATES PATENT OFFICE.

EDWARD E. WHITMORE, OF CHICAGO, ILLINOIS, ASSIGNOR TO THE CURTAIN SUPPLY COMPANY, OF NEWARK, NEW JERSEY, A CORPORATION OF NEW JERSEY.

VESTIBULE-CURTAIN MOUNTING.

1,077,660.

Specification of Letters Patent.

Patented Nov. 4, 1913.

Application filed August 7, 1913. Serial No. 783,518.

To all whom it may concern:

Be it known that I, EDWARD E. WHITMORE, a citizen of the United States, residing at Chicago, in the county of Cook and State 5 of Illinois, have invented certain new and useful Improvements in Vestibule-Curtain Mountings, of which the following is a specification.

Car vestibule curtains are ordinarily 10 mounted on the vestibule post or plate of each car and extending along the inner side of the diaphragm or detachably connected to the bolster plate of the next car whereby the interior of the accordion plaited dia- 15 phragm is covered and a smooth and pleasing interior finish is given to the passageway between two coupled cars. The curtain is usually mounted upon a spring roller so that when detached from one car it will be 20 automatically wound upon its roller and the roller will also take up any slack between the cars and maintain the curtain taut.

It has been proposed to protect the roller and improve the sightliness of the vestibule 25 equipment by mounting the roller within a casing providing access thereto for purposes of inspection, adjustment and repair, but such mounting has been cumbersome, complicated and costly to install and maintain.

30 The object of this invention is to simplify and cheapen, while at the same time increasing the efficiency of the entire device for the purposes intended. This object is attained by constructing the housing of the curtain 35 roller as a casing separate and apart from the car itself and capable of ready attachment to the vestibule post or column, the casing itself comprising a sheet metal body bent to proper shape and having its ends 40 closed by cast heads or plates carrying the bearings for the two trunnions of the roller and having integral bracket members for attachment to the car. Access to the interior 45 of the casing is provided by a door likewise of sheet metal and hinged along one edge to swing into open and closed position. The built-up features of the construction enable the housing to be adapted to curtains of different length by varying the length of the 50 sheet metal section, thus more or less widely separating the cast heads and their point of attachment to the car. This adaptability is further increased by the provision on one of the heads of an axially adjustable bearing bracket for the roller trunnions.

In the accompanying drawings and in the description based thereon is set forth a preferred embodiment of the invention. As, however, the invention is capable of embodiment in other and varied structural forms 60 the drawing and description are to be construed in an illustrative and not in an unnecessarily limiting sense.

In the drawing Figure 1 is a vertical section through a car vestibule showing the 65 vestibule curtain and its mounting in side elevation; Fig. 2 is a horizontal section on the line 2—2 of Fig. 1; Fig. 3 is a side elevation of the curtain mounting on an enlarged scale; Fig. 4 is a vertical section through the 70 curtain mounting on the line 4—4 of Fig. 6; Fig. 5 is a horizontal section through the curtain and its mounting; and Fig. 6 is a top plan view of the curtain mounting.

In the drawings the reference numeral 75 designates the roller to which is secured in any suitable manner one edge of the curtain 12, the other edge being provided with a suitable marginal reinforcement or bead 13 and provided with a handle 14 adapted to be 80 hooked over the catch 15 carried by the face plate 16 of the vestibule post 17 of the car when the curtain is in its extended position as illustrated whereby the curtain 12 extends along the inside of the diaphragms 18, 18 85 and forms a guard or interior finish therefor.

The curtain roller is provided at one end with a round trunnion 19 adapted to seat as a foot step bearing within a correspondingly shaped recess in a boss 20 of the casting 21 which is provided with an integral bracket member 22 adapted to be secured by the bolts or rivets 23 to the plate 24 carried by the vestibule post 25 of the car. At its opposite end the roller 11 is provided with 90 a trunnion 26 angular in cross section and which is adapted to engage within a correspondingly shaped opening in an L-shaped bracket 27 which bracket is provided with a slot 28 by means of which the said bracket 100 is vertically adjustable upon the bracket member 29, being held in adjusted position by means of the set screw 30. The bracket member 29 is formed integrally with and depends from a casting 31 which is provided with an integral extension 32 forming a bracket for attachment by means of the rivets or bolts 33 with the plate 24. The casting 21 is provided with an upstanding marginal flange 34 and the casting 31 with 110

a depending marginal flange 35 which flanges enter within and form a support for engagement with the lower and upper ends respectively of a sheet metal casing 36 5 which is substantially semicylindrical being bent to conform to the contour of the flanged castings 21 and 31, which latter form heads for the casing. The two edges of the casing 36 are suitably beaded at 37 and 38 to provide a finished edge, the bead 38 being cut away at intervals in order to complement in the formation of a hinge joint a similarly cut away bead 39 of a sheet metal door 40, with which cutaway portions a rod 41 operates as a pintle. The opposite edge of the door 40 is provided with a finishing bead 42, the width of the door 40 being such that a slight space 43 is left between the beaded edges 37 and 42 for the passage of the curtain 12, as clearly shown in Fig. 5. The upper portion of the door is provided with a keeper 44 with which is adapted to engage the lower beveled end of a catch 45 acted upon by the spring 46 and retractable 25 by means of a handle 47.

The cast head 31 is preferably imperforate and forms a tight cover for the casing or housing while the cast head 21 is provided with a series of apertures 48 30 through which will be discharged dust, cinders, or other foreign matter which would otherwise collect within the housing.

The length of the casing 36 and of the door 40 will be chosen to accord with the 35 length of the curtain roller to be mounted and the said casing having been positioned about the flange 34 of the cast head 21 the flange 35 of the head 31 will be slipped within the upper end of the casing and the 40 bracket 32 attached to the car at a proper height to effectually close and securely hold in position the casing 36 with its hinged door 40. The round trunnion 19 of the roller 11 will then be dropped into its seat 45 within the boss 20 and the bracket 27 placed with its opening over the angular trunnion 26 of the roller, the bracket 27 being positioned at a height to hold the trunnion in place and yet not to bind will be secured in 50 adjusted position to the bracket member 29 by means of the set screw 30 when the installation will be complete. The curtain 12 has free play within the space 43 and will be unwound from or wound upon the roller 55 11 according as its outer edge is drawn away from or permitted to approach the mounting of its roller. Ready access is afforded to the roller for installation, adjustment or removal by lifting the catch 45 and swinging 60 the door 40 upon its hinges.

The device represents a minimum cost of production and a maximum of efficiency for the purposes required, the parts being interchangeable and the device as a whole being 65 capable of being quickly installed in any

type of car without alterations in the car structure proper

I claim:

1. In a device of the character described, a vertical housing comprising an elongated headed casing and open on one side, upper and lower bearings for the roller trunnions and a door hinged at one side of and adapted to close the opening, substantially as described. 70

2. In a device of the character described, a vertical housing comprising an elongated headed casing and open on one side, upper and lower bearings for the roller trunnions, a door hinged at one side of and adapted to close the opening, and a spring catch for 80 the door, substantially as described.

3. In a device of the character described, an upright housing comprising an elongated sheet metal casing having separate top and bottom heads and open on one side, bearings for the roller trunnions within the casing and a door hinged to one side of and adapted to close the opening, substantially as described. 85

4. In a device of the character described, an upright housing comprising a semicylindrical sheet metal casing having cast top and bottom heads, bearings on the heads for the roller trunnions and a door hinged at 95 one side of and adapted to close the open side of the casing, substantially as described.

5. In a device of the character described, a housing comprising an elongated sheet metal casing having separate top and bottom cast heads and open on one side, and a door hinged to one side of and adapted to close the opening, a fixed bearing for one trunnion of the roller and an adjustable bearing for the other trunnion of the roller, 100 105 substantially as described.

6. In a device of the character described, a housing comprising a semicylindrical sheet metal casing having cast top and bottom heads, a door hinged at one side of and adapted to close the open side of the casing, a fixed foot step bearing upon the lower head for one trunnion of the roller, and an adjustable bracket on the upper head for the other trunnion of the roller, 110 115 substantially as described.

7. In a device of the character described, a housing comprising a semicylindrical sheet metal casing having cast top and bottom heads, a door hinged at one side of and adapted to close the open side of the casing, a fixed foot step bearing on the bottom head for the round trunnion of the roller, and a vertically adjustable bracket on the upper head for the angular trunnion of the roller, 120 125 substantially as described.

8. In a device of the character described, a housing comprising an elongated sheet metal casing having separate top and bottom cast heads and open on one side, a door 130

- hinged to one side of and adapted to close the opening, a fixed foot step bearing formed on the lower cast head, a fixed member depending from the upper cast head, a second member slidable vertically on the fixed member and having an angular opening to accommodate the angular trunnion of the roller, and a clamping device connecting the two members, substantially as described.
10. 9. In a device of the character described, a housing comprising a semicylindrical sheet metal casing having cast top and bottom heads, a door hinged at one side of and adapted to close the open side of the casing, the upper head substantially imperforate, and the lower head perforated to permit the escape from the housing of foreign matter, substantially as described.
10. 10. In a device of the character described, a housing comprising a semicylindrical sheet metal casing having cast top and bottom heads, a door hinged at one side of and adapted to close the open side of the casing, a fixed foot step bearing on the bottom head for the round trunnion of the roller, a vertically-adjustable bracket on the upper head for the angular trunnion of the roller, and a spring catch for retaining the door in closed position, substantially as described.
11. 11. In a device of the character described, a housing comprising an elongated casing having top and bottom heads and open on one side, and a door hinged to one side of and adapted to close the opening, a fixed bearing for one trunnion of the roller and an adjustable bearing for the other trunnion of the roller, substantially as described.
12. In a device of the character described, a housing comprising a semi-cylindrical metal casing having top and bottom heads, a door hinged at one side of and adapted to close the open side of the casing, a fixed foot-step bearing in the lower part of the casing for one trunnion of the roller, and a vertically adjustable bracket in the upper part over the other trunnion of the roller, substantially as described.
13. In a device of the character described, a housing comprising a semicylindrical metal casing having top and bottom heads, a door hinged at one side of and adapted to close the open side of the casing, a fixed foot step bearing on the bottom head for the round trunnion of the roller, a vertically adjustable bracket on the upper head for the angular trunnion of the roller, and a spring catch for retaining the door in closed position, substantially as described.
- In testimony whereof I have hereunto signed my name in the presence of two subscribing witnesses.

EDWARD E. WHITMORE.
